UNITED STATES PATENT OFFICE

2,357,580

BUILDER MOTION FOR SPINNING AND
TWISTER FRAMESLouis M. Cotchett, Hingham, Mass., assignor to
Saco-Lowell Shops, Boston, Mass., a corpora-
tion of Maine

Application August 28, 1941, Serial No. 408,638

21 Claims. (Cl. 242—43.3)

This invention relates to builder motions of the character used in spinning and twister frames. For convenience, such frames will be hereinafter referred to collectively as "spinning frames."

Builder motions of the type which have been used almost universally in commercial spinning frames for a long period of years have derived their motion from a cam acting on a roll mounted on a builder arm, this arm carrying a slidable gear segment designed to be advanced, step by step, as the winding operation progresses to vary the leverage of the arm, and, consequently, the length of traverse of the ring rail. Customarily, this motion is transmitted through a series of lever arms and cross shafts to the lower ends of the lifter rods which support the ring rail. The reciprocating movements of the ring rail produced by the builder motion are designed to be so related to the rate of delivery of yarn to the bobbins that yarn packages of the desired contour will be produced automatically by the machine. Usually the contour desired is a generally cylindrical form, tapered at one or both ends. The manner in which the yarn body is built up, however, depends upon the requirements of different winds, such as filling winds, warp winds, and others.

While these builder mechanisms work well in the great majority of cases, they necessarily are provided with a multiplicity of adjustments designed to accommodate those variations customarily encountered in practice. In making these adjustments, however, especially when they are required to deal with unusual conditions, an extraordinary amount of time, labor and skill is required to bring about that inter-relationship of the parts necessary to make the machine build yarn packages of the desired form. In some measure these difficulties arise from the fact that so many of the movements are transmitted through, or are created in, levers, while the ultimate motion of the ring rail is a reciprocating movement in a straight line.

The present invention aims to devise a builder motion in which these difficulties will be eliminated, or at least greatly minimized. Stated more specifically, it is an object of the invention to simplify the motions involved in producing the desired movements of the ring rail, to eliminate many of the adjustments required by the common forms of builder mechanisms, to facilitate those adjustments necessary to shift from one type of wind to another, and to devise a mechanism of this character which will be highly

reliable and will be substantially trouble-free over a long period of service.

The nature of the invention will be readily understood from the following description when read in connection with the accompanying drawings, and the novel features will be particularly pointed out in the appended claims.

In the drawings,

Fig. 1 is a side elevation, with parts in vertical section, showing portions of a builder motion embodying this invention applied to a spinning frame;

Fig. 2 is a horizontal, sectional view approximately on the line 2—2, Fig. 1;

Fig. 3 is a vertical, transverse, sectional view approximately on the line 33, Fig. 1;

Fig. 4 is a vertical, sectional view, approximately on the line 4—4, Fig. 2, showing parts at opposite ends of a cross shaft, certain of the intermediate parts being omitted;

Fig. 5 is a side elevation of the motion generating mechanism;

Figs. 6, 7 and 8 are views, somewhat diagrammatic in character, illustrating different positions of the butterfly toggle mechanism which assists in shifting the clutch;

Fig. 9 is a vertical, sectional view of certain of the parts shown in Fig. 5 with other parts shown in elevation;

Figs. 10 and 11 are sectional views approximately on the lines 10—10 and 11—11, respectively, of Fig. 9;

Fig. 12 is an angular view of the control shafts and the pick mechanism for driving them;

Figs. 13 and 14 are front elevations of the pick mechanism showing certain of the operating parts in different positions;

Figs. 15 and 16 are diagrammatic views of different winds and illustrates typical positions of the indicator or control fingers required in building them;

Fig. 17 is a fragmentary view showing the preferred method of locking the end of the steel band to a drum or disk; and

Fig. 18 is a similar view showing a bobbin pattern in cooperative relationship to the control fingers.

Preliminary to a detailed description of the mechanism shown in the drawings, it may be pointed out that the present invention utilizes a screw-threaded shaft as the primary driving element of the builder motion, instead of the customary cam, and it meshes with and drives a secondary or driven member. As shown, the prime mover of this mechanism is a screw hav-

ing threaded engagement with, and adapted to drive, a nut. Connections running from this nut to the lifter rod transmit the desired traverse motion to the ring rail. Since this motion is of a reciprocating character, means is provided for automatically reversing the direction of rotation of the screw at the desired points in the path of travel of the nut, and additional means is provided whereby the points at which these reversals take place may be manually adjusted. The mechanism also includes means for automatically adjusting those points as required in connection with the building of different types of yarn packages.

Referring to Figs. 1, 2, 5 and 9, the screw which forms the prime mover of the builder motion is shown at 2 and the nut at 3. The left-hand end of the screw shaft 2 is connected by a pin 4 with a bushing 5 on which is mounted a clutch member 6, this member being compelled by the pin 7 to revolve with the bushing but also being axially slidable on the bushing. As shown in Fig. 5, the opposite ends of the clutch member are toothed to engage complementary teeth formed in the end faces of gears 8 and 9, both revolving on the bushing 5, and these two gears are driven in opposite directions by any convenient source of power. Consequently, by shifting the central clutch member 6 into engagement with one or the other of these gears, the screw 2 may be revolved in either direction desired. Such rotation produces an axial movement of the nut 3 and the motion of this member is transmitted through a rod 10, and a control block 12 pinned to it, to a metal strap 13 which forms the first element of a series of connections for transmitting motion of the nut to the ring rail. In this connection it may be pointed out that the reason for the rod 10 and block 12 is to avoid interference with the driving cylinder C, Fig. 3, for the spindles. If it were not for this necessity the screw 2 would be continued and the nut 3 would take the place of the block 12. Thus the latter may be considered the equivalent of the former since the two are rigidly connected together and share the same movements.

Reversal of the clutch member 6, and therefore of the screw 2, is initiated by the movement of the nut and the control block 12. For this purpose two control stops or fingers 14 and 15, Figs. 2 and 12, are operatively engaged with the lower and upper screw-threaded control shafts 16 and 17, respectively, and they are both guided on a rod 18. As best shown in Fig. 3, the lower sides of these two control fingers are cut away, their threaded engagement with the respective control shafts being confined to the upper sides of these shafts, so that either can be swung out of engagement with its respective shaft, when desired, and slid along the guide rod 18 to change its setting on the shaft. For this purpose the outer end of each stop is provided with a thumb piece a, as best shown in Fig. 12.

It will be observed that the control block 12 is positioned between the stops, and since it is secured to the nut 3 for longitudinal movement therewith, it will engage one or the other of these stops or fingers at points in the travel of the nut which depend upon the positional relationship of the control block and the fingers. The control screws 16 and 17 are supported for limited axial sliding movement in bearing plates 20 and 21, both rigidly secured to the frame, so that when the control block engages the finger 14 during its movement toward the left, Figs. 1 and

12, it will move the shaft 16 endwise in the same direction, and upon engagement with the finger 15, as it moves toward the right, it will move the upper screw 17 in the latter direction. These two shafts pass through a block 22, and they are provided with shoulders and collars so arranged that they carry this block with them in any longitudinal movement imparted to either of them by the movement of the control block 12, as just described. As above indicated, such movements are utilized to shift the direction of rotation of the screw 2.

Referring to Fig. 9, it will be seen that the pin 7 passes through a hole provided to receive it in a shaft 24, coaxial with the lead screw 2, so that it is driven in unison with the clutch member 6. This shaft is slidable axially in the bushing 5, carrying the pin 7 with it, and it is utilized to shift the clutch member 6 from either of its operative positions to the other. To this end its outer end portion is grooved to receive two blocks 25 which are swiveled in the block 26 by means of pivot pins 27-21. Mounted at right angles to the shaft 24 is a rock shaft 28, supported in a stationary bracket 30, and this shaft carries an eccentric 31 at one end thereof, preferably supported in needle bearings in a socket formed in the block 26. At its outer end an arm 32, Figs. 5 to 8, is secured to the rock shaft. It will be seen that if this arm is swung forward and backward, thus rocking the shaft 28 and the eccentric 31, the latter will move the block 26 toward the right or left, Fig. 9, depending upon the direction of such swinging movement, and that this movement of the block will be transmitted through the parts 27 and 25 to the shaft 24, the pin 7 and clutch member 6, thus shifting the clutch from one of its operative positions to the other.

It is important that this clutch shifting movement take place quickly and positively, and that any possibility of the clutch being stopped in an intermediate position be obviated. Moreover, since this mechanism is required to operate hundreds of times in the course of a day's run, and a single failure may have relatively serious consequences, it is important that the mechanism by which such shifting movements are produced shall be extraordinarily reliable. Accordingly, one of the features of the present invention is a novel "load-and-fire" mechanism which takes the form of a "butterfly toggle."

Referring to Figs. 5, 6 and 11, it will be observed that this mechanism comprises a lever 33 fulcrumed at 34 on the frame piece 30. A link 35 connects this lever with the block 22 previously referred to. Pivoted to the upper end of this lever at 36 is a head 37, Fig. 11, in which the upper end of a rod 38 is rigidly fixed, this rod depending downwardly and having a block 40 slidably mounted thereon. A pin 41 pivotally connects the lower end of the arm 32 with this block, and a spring 42 is interposed between the block and a nut 33 threaded on to the lower end of the rod 38. This toggle mechanism, therefore, comprises two toggle links with their ends overlapped and connected by a third or intermediate spring link.

Assuming that the parts are in the position shown in Fig. 6 and that the block 22 has just begun to move toward the left in order to effect a reversal of the direction of rotation of the screw 2, this movement is transmitted through

the link 35 to the lever 33, thus swinging its upper end in a counter-clockwise direction. As the pivot point 36 moves toward the left it carries the upper end of the rod 38 with it, the block 40 and the rod swinging in unison about the pivot 41 as a center. During this action the rod 38 is pulled upwardly through the block 40, thus compressing the spring 42, storing energy in it, and consequently setting up a tension between the pivots 36 and 41, Fig. 7. This force obviously tends to swing the arm 32 in a clockwise direction and such force will be equal to the expansive effort of the spring multiplied by the moment arm from the center of the pivot 28 to a common center line connecting the pivots 36 and 41. The continued counter-clockwise movement of the lever 33 obviously increases this moment arm until it reaches a value sufficient to snap the arm 32 over into the position shown in Figs. 5 and 8. Thereupon the spring 40 acts to line up the pivots 36 and 41 with a pivot 34.

It will thus be observed that the arm 32 is carried over into its new position by the action of the spring 42 during a continuation of a reversing movement initiated by a force transmitted to the lever 33, and that the energy of the spring acts in the same direction as the movement of the lever and only after the lever has passed its dead center position. All the parts of this butterfly toggle mechanism are in equilibrium initially, tending to maintain the existing clutch engagement, and this condition continues up to the instant that the energy of the spring 42 is released and the clutch is shifted, whereupon a new equilibrium is established serving to retain the clutch in its new position.

When the control screw 17 moves the block 22 toward the right a reversal of the operations just described takes place, and the toggle mechanism snaps the clutch member 6 back into its initial position.

These parts of the builder motion mechanism so far described serve to produce a traversing movement of the nut 3, to reverse that movement at points determined by the adjustment of the stop fingers 14 and 15, to produce such reversal substantially instantaneously, and to afford convenient means for adjusting independently the points at which such reversal will take place. These are all the building operations required in making a spool wind, but in producing other types of winds, such as a filling wind or a warp wind, it is necessary to feed one, or both, of the points of reversal lengthwise of the line of traverse. The builder motion shown includes mechanism for producing such feeding or adjusting movements automatically. This mechanism effects the results desired through rotation of the control screws 16 and 17. By the relative direction and speed of this rotation they may be made to feed the stop fingers 14 and 15 in the same or opposite directions, and at the same or different speeds.

Such rotation of the control screws is produced by means of a pick motion which is universal in the sense that by adjustment of shields to hold the pawls out of engagement with the ratchets, either screw may be picked or rotated in either direction and at a predetermined speed in accordance with the number of teeth which the pawl is permitted to pick up in its stroke, the stroke being constant. It is desirable, however, that such rotative movement of the control screws be prevented at the moment of reversal

since reversal is accomplished by the threaded engagement of the stop fingers or nuts with the screws and the pressures so created tend to bind the screws against a pick rotation at this time with a consequent high resistance to movement by the pick mechanism. The construction shown in the drawings therefore is so organized that picking occurs only during a brief interval immediately after each reversal.

Referring to Figs. 5, 9 and 10, it will be seen that two ratchet wheels 44 and 45, each having four teeth only, are mounted on a sleeve 46 and keyed thereto, this sleeve encircling a reduced portion of the lower control screw 16. Mounted loosely on this sleeve to rock thereon, and immediately beside the wheel 45, is an arm 47 carrying two pawls 48 and 49, respectively. Both pawls rock on a common pivot 50 and they are arranged to engage the respective ratchet wheels 44 and 45. Pivoted to the arm 47 is a pitman 51 actuated by an eccentric 52 which is keyed to the sleeve 5 above referred to. Since the eccentric is driven in unison with the lead screw 2, the rocker arm 47 is oscillated so long as the screw is being revolved. To control the pawls a pin 53, Figs. 5 and 10, projects laterally from the block 22 under the pawl 49. When in the position shown in Fig. 10, it lifts this pawl out of contact with its ratchet wheel and thus holds it in an inoperative position. At this time, therefore, the pawl 48 is allowed to engage its ratchet wheel 44 and it acts to rotate the wheel four teeth and thereafter runs idly since it then rides on the smooth edge of the wheel. Upon the next reversal of the screw 2, the block 22 is moved into such a position as to allow the pawl 49 to drop into a cut-out or groove in the upper side of the pin. The movement so permitted is sufficient to let the pawl engage its ratchet wheel 45, whereupon it picks that wheel four teeth in the reverse direction to that produced by the pawl 48, but its action also is then stopped because it has reached the end of the toothed portion of the wheel. When the pawl 49 is brought into action, a pin 54, Fig. 10, projecting laterally from it, engages the tail portion of the pawl 48, and because 49 is much heavier than 48, it lifts the latter out of engagement with its ratchet wheel 44. Thus upon any reversal of the screw 2 one pawl or the other is brought into operation through the longitudinal movement of the pin 53, and the picking operation of one pawl restores the ratchet wheel of the other to a position suitable for the next operation of the latter.

The step-by-step rotative movements in opposite directions imparted to the sleeve 46 in the manner just described serve to oscillate an arm 55, Figs. 5, 9, 12 and 13, about the axis of the sleeve, and this arm carries two pawls 56 and 57 adapted to engage, respectively, the oppositely toothed ratchet wheels 58 and 59, both of which are keyed to the end portion of the shaft 16, as shown in Fig. 5. A shield 60 carried by a hub member 61 which is centered on the end of the shaft 16 but is mounted for rotary adjustment in the plate 62, has a circumferential extent somewhat greater than the distance between the pawls, and the pawls carry pins *p*—*p*, Figs. 9 and 13, lying sufficiently within the path of adjustment of the edge of the shield so that this shield may be utilized to hold either or both pawls in their inoperative positions, or, to allow either of them to operate. Any rotative movement so imparted to the ratchet wheels, however, is trans-

mitted to the control screw 16 and serves to feed its respective control stop or finger 14 axially of the screw. The number of teeth which either pawl 56 or 57 is allowed to pick at one stroke is controlled by the shield and a knob 63 provided with a graduated edge, as shown in Fig. 13, is mounted on the outer end of the hub 61 where it serves as a convenient means for adjusting the position of the shield. These graduations cooperate with an index mark *e*, Fig. 13, provided on the outer face of the plate 62.

Connections similar to those just described are provided to operate the upper control screw 17. For this purpose the sleeve 46 is connected by gears 64 and 65 to another sleeve 66, similar to the sleeve 46 and similarly mounted, and the latter sleeve supports an arm 67 carrying pawls 69 and 70, Fig. 13. These pawls cooperate with oppositely toothed ratchet wheels 71 and 72 and with a shield 73, the ratchet wheels being keyed to an extension of the control screw 17, all substantially as described in connection with the lower control screw 16. An adjusting knob 74 corresponds to that shown at 63. Usually the upper ratchet wheels control the adjustments at the lower end of the bobbin and the lower wheels those at the upper end, although this arrangement can be reversed if desired.

The builder unit above described can be made to produce the various reciprocating movements of the nut 3 required for the purpose of building practically any form of yarn package. Transmission of these movements to the lifter motion is effected through the flexible steel band 13, one end of which is anchored to the control block 12. From this point it extends forward approximately horizontally and is given a partial wrap around and is secured to a drum 75, Fig. 2, fast on the cross shaft 76. Keyed on the opposite ends of this shaft are two drums 77-77, similar to the drum 75, and a steel band 78, Fig. 1, having a partial wrap around the drum 77 there shown, extends downwardly along the side of the lifter rod 80, its lower end being wrapped around the lower end of the rod and riveted thereto, in the manner best shown in Fig. 4. At its upper portion this lifter rod takes the form of a tube and it encircles and slides on a guide rod 81 which usually is anchored to the frame both above and below the path of traverse of the tubular section of the rod. This and a similar rod at the opposite end of the frame section shown in Fig. 1, support the ring rail 82, the latter being mounted in clamps 83-83 which connect it with the upper ends of the lifter rods. Another pair of lifter rods at the opposite side of the frame, similar to the pair just described, support a second ring rail in the same manner.

It will be evident that the weight of the ring rail 82 and the parts carried thereby is transmitted through the connections just described to the control nut 12, thus placing all of the flexible steel bands 13 and 78 under tension. The weight of these parts is utilized to produce the lowering movement of the rail, such movement, however, being under the control of the screw and nut prime mover, and the upward movement of the rails is produced by this screw and nut assembly.

In each succeeding section a cross shaft 76 is provided and it has lifter elements associated with it like those shown in Figs. 1 and 2. A steel band 84, Fig. 2, having a partial wrap around a second drum 85, beside the drum 75 and also secured to the cross shaft 76, transmits both the

lifting movement and the control effort of the screw and nut assembly to the next cross shaft, and these connections are repeated through successive sections to the end of the frame.

5 A convenient method of anchoring the end of the steel band 78 to the drum 77 is shown in Fig. 17. Here a cylindrical slug or plug 86, pierced with a hexagonal hole, is set into a socket in the drum with its axis parallel to that of the drum, and it is releasably locked there by a pin 87 grooved at one side on such a radius as to fit snugly against the surface of the plug. A set screw 88 is threaded into the drum and serves, when tightened, to force the pin inwardly and thereby to lock the plug against rotation. However, by releasing the set screw and rotating the plug, the effective length of the steel band may be changed and such an adjustment is useful in making the initial set-up. The end 10 portion of the band being wrapped around the plug and the extreme tip inserted in a radial slot formed in it, anchors the band securely to the drum.

The control screws and other parts of the 15 builder unit extend for a substantial distance into the first section of the frame, as shown in Fig. 1, so that the cross shaft 76' at the head end of the section cannot conveniently be operated in the same manner as are the other cross shafts. A 20 satisfactory arrangement for driving this first cross shaft comprises a second band 90 having a partial wrap around one of the drums 77, anchored thereto, and also partially wrapped around and anchored to a drum 77' at the same side of the frame as the drum 77. This connection therefore revolves the cross shaft 76' in unison with the cross shaft 76 of the first section, and since the connections between both cross shafts and their respective lifter rods are the same, they are 25 operated in unison.

If it is desired to traverse the thread board 81, Figs. 1 and 3, this may conveniently be done by mounting the guide rods 81 for vertical movement, supporting the lower end of each guide rod on a pin, such as that shown at 92 in Figs. 1 and 4, this pin projecting laterally from a disk 93 mounted below and somewhat behind the disk 77'. A band 94, Figs. 1 and 4, one end of which is anchored in the disk 93 and the opposite end in a small disk 95 on the cross shaft 98, Fig. 4, transmits motion from the latter disk to the former, and the latter derives its motion from a pin 96 set into any one of a series of holes in the disk 77'. As the disk 77' revolves during the rise 30 of the ring rail, the pin picks up an arm 97 projecting radially from the disk 95, and rigid therewith, and compels the latter to rotate with the main disk. This, in turn, compels the disk 93 to 35 revolve at a much slower speed than the disk 77', but in such a direction as to make the pin 92 lift the rod 81 and the thread board 81. Another band 99 runs from the disk 93 to a similar disk 100 at the opposite end of the section and this disk is mounted in the same relationship to the rod 81 at this end of the section as is the disk 93 at the opposite end. Consequently, both ends 40 of the thread board are raised simultaneously and at the same speed.

As the thread board descends by its own 45 weight, but under control of the builder screw, a reverse rotation of the disks 93 and 100 occurs, and this movement is stopped after the thread board has dropped the desired distance, usually only an inch or two, by the engagement of the arm 97 with a stop pin 101 secured in a part

rigid with the bracket 102. The thread board rests in its lowered position while the ring rail completes its downward movement and until it is again raised far enough to cause the pin 96 to engage the arm 97 again and to pick it up in rotation. An extension 103 of the band 99 runs into the next section to operate a disk like the disk 100 in performing the same functions and these connections are repeated through succeeding sections.

At the opposite side of the first section from that shown in Fig. 1, the connections above described are repeated except that the disk 95', corresponding to the disk 95, instead of being driven through an arm like the arm 97, is keyed to the shaft 98 to which also the shaft 95 is keyed, so that these two disks are driven in unison. The connections between this disk 95' and its rod 81 are like those above described between the corresponding parts at the opposite side of the frame.

The fact that the initial builder movement generated by the mechanism described is in a straight line, and that the transmitting mechanism produces a straight line movement of the ring rail having the same linear characteristic as that originally generated, is an important advantage in facilitating the adjustments required in shifting from one type of wind to another. The very simple nature of these adjustments also contributes to this result. The method usually followed is to secure one of the bobbins on which the yarn is to be wound on the side wall of the frame at some readily accessible point immediately above the path of movement of the control fingers or nuts 14 and 15. Such a bobbin, or a replica of it, usually split lengthwise, is shown at P in Fig. 18 secured by two screws immediately above and parallel with the path of adjustment of the pointers b—b on the ends of said fingers, these fingers projecting through a slot formed in a side plate of the machine casing.

In producing a new wind it is simply necessary to set the fingers b—b opposite the points on the bobbin at which the reversal of the winding operation should take place, and then to adjust the knobs 63 and 74, Fig. 13, to produce the desired number of picks in the direction required by the package building operation. Assuming, for example, that a filling-wind is to be produced, as shown in Fig. 15, the right-hand finger will be set initially at the base of the bobbin and the left-hand finger at a distance away from it, corresponding to the length of traverse desired. The building of this package requires that both these fingers be traversed toward the left at a uniform rate. Consequently, the knobs 63 and 74 are set in some such positions as those shown in Fig. 13. Both knobs are here shown adjusted for an up-pick of eight teeth per pick. Each pick on either ratchet wheel will, for example, result in producing an adjusting movement of the fingers b—b equal to a small predetermined fraction of an inch, depending upon the size of yarn used. In this connection it should be remembered that upon one reversal the pawls move backward or idly over the teeth and upon the next reversal they advance the ratchet wheels. Consequently, the feeding movement of the points of the reversal of the ring rail are such as to build up a yarn body in essentially the manner illustrated in Fig. 15. The pointers b—b are here shown at intermediate positions in the production of the package.

In building a warp-wound bobbin, as shown in Fig. 16, the pointers b—b are set initially at the

opposite ends of the package to be made. In this instance the points of reversal are to be traversed simultaneously toward each other at approximately the same rate. Accordingly, the shields are set in some such positions as those shown in Fig. 14, the upper knob 74 controlling the movement of the right-hand pointer b being set for an up-pick of, say, seven teeth and the lower knob 63 being set for a down-pick of the same number of teeth.

Any of the recognized forms of packages can be produced by other adjustments of the pointers and of the pick mechanisms, as will be evident to those skilled in this art. The adjustments required for this purpose are, however, extraordinarily simple and can be made very easily, quickly, and with a minimum of effort. This is a very important practical advantage of the builder motion provided by the invention.

It will also be evident that the mechanism itself is relatively simple in construction, its various parts are of such a nature that they are not liable to get out of order, they require relatively little attention, and the mechanism is, accordingly, extremely reliable.

While I have herein shown and described a typical embodiment of my invention, it will be evident that the invention may be embodied in other forms and that various changes in the embodiment shown may be made while still utilizing the essential features of the invention. For example, it is obvious that the flexible bands above referred to may be replaced by chains or other flexible elements. Also, that the drums 75 and 85 may be combined into a single drum or pulley or, if desired, these two could be combined with the drum 71 on the ends of the shaft 76 to form a cylinder serving the same purposes as do the separate units. These and various other modifications and variations in design can be made within the spirit and scope of the invention.

Having thus described my invention, what I desire to claim as new is:

1. In a spinning frame, the combination with a ring rail and lifter elements supporting it, of a screw, a nut mounted thereon, means for transmitting motion of said nut to said elements, mechanism for revolving said screw in opposite directions, said mechanism being reversible, and including a clutch element shiftable into engagement with cooperating clutch members at opposite sides of it, means actuated by the movement of said nut for initiating such reversal, and a toggle mechanism actuated by the movement of said nut and including a spring link connecting two overlapped main toggle links for completing said reversal with a snap action.

2. In a spinning frame, the combination of a ring rail, a lifter rod connected with said rail to impart operative movement thereto, a main screw, mechanism for revolving said screw in opposite directions around its own axis, a nut mounted on said screw to be traversed thereby, means for transmitting motion of said nut to said lifter rod, two rotary control screws, two control nuts mounted, respectively, on said control screws in threaded engagement with them, and for adjustment lengthwise of said control screws independently of them, means supporting said control screws and said control nuts in such a relationship that the control nuts may be engaged and moved lengthwise by a part movable with the nut on the main screw, and means arranged to be actuated by the movement of the

control nuts so produced to reverse the direction of rotation of said main screw.

3. In a spinning frame according to preceding claim 2, in combination with mechanism for driving said control screws, said mechanism being adjustable to feed one or both of said control nuts lengthwise of its respective control screw while the spinning operation progresses.

4. In a spinning frame according to preceding claim 2, in combination with two pawl and ratchet mechanisms for driving the respective control screws intermittently, each of said mechanisms being adjustable to vary the movements imparted to the control screws independently of each other and in accordance with the requirements of different winds.

5. In a spinning frame according to preceding claim 2, in combination with mechanism for rotating said control screws step-by-step as the spinning operation progresses, including pawl and ratchet devices for driving the respective screws and a third pawl and ratchet mechanism for driving the first two, said third pawl and ratchet mechanism being driven from the mechanism which drives said main screw, and the first mentioned pawl and ratchet mechanisms being adjustable independently of each other to vary the rotative movements imparted to the respective control screws in accordance with the nature of the wind to be produced.

6. In a spinning frame according to preceding claim 2, in combination with mechanism for driving said control screws, said mechanism being adjustable to feed one or both of said control nuts lengthwise of its respective control screw while the spinning operation progresses, and automatic means for so controlling the feeding movements of said control nuts that such movements will not occur during the reversal of the direction of rotation of the main screw.

7. In a spinning frame, the combination with a ring rail and an upright lifter rod therefor, of a drum mounted to revolve on a horizontal axis with its peripheral edge close to the path of travel of said rod, a flexible band having one end anchored to said drum and its opposite end secured to the lower part of said rod with an intermediate portion of said band positioned immediately beside said rod, whereby rotation of said drum in one direction lifts the rod, said drum having a plug positioned therein near the periphery of the drum for rotary adjustment about an axis substantially parallel to the drum, the end of said band being secured to said plug and the part thereof adjacent to the end being wrapped around the plug, and means for releasably securing the plug in its various positions of rotary adjustment.

8. In a spinning frame, the combination with a ring rail and lifter elements supporting it, of a screw-threaded shaft, mechanism for revolving said shaft around its own axis in opposite directions, a device meshing with the screw threads on said shaft to be driven thereby, connections for transmitting motion of said device to said elements, means operable to reverse the direction of motion of said device by said screw threaded shaft, means for automatically adjusting the points of reversal of said device along its path of travel and operable to move said points at the same or different rates, as desired, while the spinning operation continues uninterruptedly, and connections between said mechanism and said adjusting means for maintaining a predetermined time relationship between the rotation of

said shaft and the operation of said adjusting means whereby different winds may be produced at will.

9. In a spinning frame, the combination with a ring rail and lifter elements supporting it, of a screw-threaded shaft, mechanism for revolving said shaft around its own axis in opposite directions, a device meshing with the screw threads on said shaft to be driven thereby, connections for transmitting motion of said device to said elements, means operable to reverse the direction of motion of said device by said screw threaded shaft, and power driven mechanism for automatically adjusting either or both points of reversal of said device along its path of travel, as desired while the spinning operation continues uninterruptedly, whereby different winds may be produced at will, and connections between said mechanisms for driving one from the other and maintaining a predetermined time relationship between the rotation of said shaft and said adjusting operation.

10. In a spinning frame, the combination with a ring rail and lifter elements supporting it, of a screw-threaded shaft, mechanism for revolving said shaft around its own axis in opposite directions, a device meshing with the screw threads on said shaft to be driven thereby, connections for transmitting motion of said device to said elements, means operable to reverse the direction of motion of said device by said screw threaded shaft, and power driven mechanism operated in timed relationship to the motion of said device for automatically adjusting the points of reversal of said device along its path of travel, said adjusting mechanism being itself adjustable to move said points of reversal in the same or opposite directions, as desired.

11. In a spinning frame, the combination with a ring rail and lifter elements supporting it, of a screw-threaded shaft, mechanism for revolving said shaft around its own axis in opposite directions, a device meshing with the screw threads on said shaft to be driven thereby, connections for transmitting motion of said device to said elements, means operable to reverse the direction of motion of said device by said screw threaded shaft, and power driven mechanism operated in timed relationship to the motion of said device for automatically adjusting the points of reversal of said device along its path of travel, said adjusting mechanism being itself adjustable to move said points of reversal in the same or opposite directions and at the same or different speeds, as may be necessary for different winds.

12. In a spinning frame, the combination with a ring rail and lifter elements supporting it, of a screw-threaded shaft, mechanism for revolving said shaft around its own axis in opposite directions, a device meshing with the screw threads on said shaft to be driven thereby, connections for transmitting motion of said device to said elements, means operable to reverse the direction of motion of said device by said screw threaded shaft, mechanism for automatically adjusting the points of reversal of said device along its path of travel independently of each other, and connections between said mechanisms for driving one from the other and maintaining a definite time relationship between the rotation of said shaft and said adjusting operation.

13. In a spinning frame, the combination with a ring rail and lifter elements supporting it, of a screw-threaded shaft, mechanism for revolving said shaft around its own axis, a device mesh-

ing with the screw threads on said shaft to be driven thereby, connections for transmitting motion of said device to said elements, means driven by said shaft for reversing its own direction of rotation and, consequently, reversing the direction of movement of said device, said means including a clutch element shiftable into engagement with cooperating oppositely driven clutch members at opposite sides of it, and power driven mechanism for automatically adjusting the points of reversal of said device along its path of travel, said adjusting mechanism comprising two control screws, two stops driven by said respective screws, said stops being adjustable along said screws independently of the screws, and means for driving said control screws including a reversible pawl and ratchet mechanism operable automatically to drive the screws through a predetermined angular distance in one direction and then through an equal angular distance in the opposite direction.

14. In a machine according to preceding claim 13, a construction in which said pawl and ratchet mechanism automatically returns to rest in a predetermined condition after each cycle of its operations, and means arranged to be actuated by said shaft reversing means for initiating the operation of said pawl and ratchet mechanism at substantially the completion of said shaft reversing operation.

15. In a machine according to preceding claim 13, a construction including means for limiting the operation of said pawl and ratchet mechanism to a brief interval of time immediately after each reversal of rotation of said screw-threaded shaft.

16. In a machine according to preceding claim 13, a construction in which two pawl and ratchet mechanisms are connected with said control screws, respectively, to drive them, said reversible pawl and ratchet mechanism being connected with the first two pawl and ratchet mechanisms to drive them in both directions, said reversible pawl and ratchet mechanism being constructed to make a predetermined number of picks in both directions after its operation is once initiated and then to stop, and means controlled by said shaft reversing mechanism for initiating the operation of said reversible pawl and ratchet mechanism.

17. In a spinning frame, the combination with

- 5 a ring rail and lifter elements supporting it, of a screw-threaded shaft, mechanism for revolving said shaft around its own axis, a device meshing with the screw threads on said shaft to be driven thereby, connections for transmitting motion of said device to said elements; and mechanism operable to reverse the direction of rotation of said screw-threaded shaft comprising a member shiftable from one operative position to another, a spring actuated toggle mechanism for shifting it from either of said positions to the other with a snap action, and means arranged to be operated by the screw-threaded portion of said shaft for swinging said toggle past its dead center position in opposite directions to initiate said reversing operation, said mechanism serving to hold said member against movement out of its operative position until the instant of shifting by said snap action.
- 10 18. In a spinning frame according to preceding claim 17, a construction in which said toggle mechanism includes two main toggle links, with portions overlapping each other and adapted to swing into and out of common alignment, and a spring link pivotally connecting said overlapping portions of said main links.
- 15 19. In a spinning frame according to preceding claim 17, a construction in which said toggle mechanism includes two main toggle links, the two links being pivoted at points spaced widely apart and extending toward and overlapping each other, and a compression spring link pivotally connecting the overlapping ends of said main links.
- 20 20. In a spinning frame, the combination with a ring rail and a builder motion connected therewith to reciprocate said rail, of control fingers mounted closely adjacent to each other in a readily accessible position on said frame for adjustment toward and from each other, and a bobbin pattern associated with said fingers for adjustment of the latter therealong, said builder motion including parts operable automatically to reverse the motion of said ring rail and the points of reversal being controlled by the positions of said respective fingers.
- 25 21. A spinning frame as defined in preceding claim 8, in combination with manually adjustable means for predetermining the rate at which said adjusting movement will be produced.

LOUIS M. COTCHETT.
